UNITED STATES PATENT OFFICE.

VICTOR KOUNS, OF MOKANE, MISSOURI.

DUMPING-CAR.

SPECIFICATION forming part of Letters Patent No. 764,476, dated July 5, 1904.

Application filed April 19, 1904. Serial No. 203,890. (No model.)

To all whom it may concern:

Be it known that I, VICTOR KOUNS, a citizen of the United States, and a resident of Mokane, in the county of Callaway and State of Missouri, have invented a new and Improved Dumping-Car, of which the following is a full, clear, and exact description.

This invention relates to improvements in side-dumping cars, the object being to provide a means whereby all of the cars in a train may be simultaneously dumped, the dumping mechanism being operated from the locomotive, thus resulting in a saving of time in discharging train-loads.

15 I will describe a dumping-car embodying my invention and then point out the novel features in the appended claims.

Reference is to be had to the accompanying drawings, forming a part of this specification, 20 in which similar characters of reference indicate corresponding parts in all the figures.

Figure 1 is a transverse sectional view of a dumping-car embodying my invention. Fig. 2 is a section on the line $\alpha\alpha$ of Fig. 1. Fig. 3 25 is a bottom plan view. Fig. 4 is a sectional detail showing the car-platform in dumping position. Fig. 5 is a sectional view of one of the dump-actuating wheels. Fig. 6 is a section on the line $\gamma\gamma$ of Fig. 1, and Fig. 7 shows 30 a train of the dumping-cars.

As the dumping mechanism is alike in each car, a description of one will answer for all, it being understood, however, that the mechanism of the several cars is actuated from a single point, as will be hereinafter described.

Referring to the drawings, 1 designates the truck of a car, having standards 2 at the ends, with which the platform 3 has swinging connection. As here shown, the platform has on 40 its under side a central beam 4, from which trunnions 5 extend into the standards 2. Arranged underneath the platform is a rock-shaft 6, on the ends of which are dump-actuating wheels 7. Each dumping-wheel for a portion 45 of its circumference has a peripheral channel, and the side walls of the channel are provided with notches 8 to receive a block or ball 9, carried by chains 10, and each wheel 7 is also provided with antifriction-rollers 11. As

here shown there are four antifriction-rollers 50 in each wheel; but the number may be varied without departing from the spirit of my invention. The chains 10 have spring yielding connections 12 with the platform 3 near the sides, and the said chains pass underneath 55 rollers 13, mounted in the truck-frame. The dump-controlling wheels 7 are provided with projections or lugs 14, designed to engage between latch-plates 15 16, pivoted at their upper ends between straps 17 and the frame 60 portions of the truck. The upper portions at the inner sides of these latches are curved, and their top ends are curved or cam-shaped. The latches 15 16 of a pair are connected by a spring 18, and the latches are movable between the frame-truck and guide-plates 19. To prevent the wheels 7 from moving too far, I employ stops 7^a at opposite sides for engaging with the lugs 14.

Arranged underneath the rock-shaft 6 is a 70 shifting shaft 20, which has bearings in hangers 21, attached to cross-bars 22, and also has a bearing in a standard 23. At the ends the shaft 20 has downwardly-extended arms 24, carrying rollers 25, which engage between the 75 lower ends of the latches 15 16, and at about the center of the shaft 20 is a downwardly-extended arm 26, the lower end of which moves between plates 27 28, secured to a cross-bar 29. These plates are provided with perforations at opposite sides of the arm 26, so that a locking-pin 30 may be placed in the perforations at one side of the arm, depending upon the direction the platform is to be dumped. In fact, when the train is moving 85 with the load pins may be placed at each side of the arm, so as to hold the shaft 20 rigidly in position.

A coiled spring 31 is connected at one end to the shaft 20 and at the other end to a crank 90 member 32 formed in the shaft 6. This spring 31 serves to yieldingly hold the rock-shaft in its released position when the platform is in dumping position and with a lug 14 in engagement with a latch 7^a, so that the ball 9 will 95 readily enter the notch 8 for returning the platform to normal position.

From a winding-drum 33, supported on a

truck 34, attached to the locomotive 35, operating cables 36 37 extend along opposite sides of the several cars and underneath the platforms. These cables are reversely wound 5 on the drum, so that when operating the drum to dump the several car-platforms in one direction the cable on the opposite side will be wound on the drum, keeping the same taut. The drum is operated by an engine 38, which 10 receives steam from the locomotive.

The cables engage with pulleys 39, supported on the truck 1 at the lower portion and at the ends, and then pass around pulleys 40, carried by the truck, thence through pulleys 41, 15 attached to the platform 3, and around pulleys 42, attached to the arm 26. At the rear ends the cables have spring yielding connection 43 with the rear end of the rear car, thus providing cushions to prevent possible breaking 20 of the cables when sudden strain is given to the same. The sections of the cables between the cars are protected from dirt, stones, or the like by means of platforms 44, each platform being hinged to the rear end of a car 25 and designed to engage with a part of the truck of the car immediately in the rear, as clearly illustrated in Fig. 7.

In coupling the cars of a train the coupling links and pins should be made very strong, so 30 as to reduce possibility or danger of breaking the train apart, and it may be here stated that with my improved method of dumping the several cars of a train the cars may be kept connected for any desired length of time. It 35 may be further stated that the train is moved by either a pushing or pulling operation of the locomotive, as may be desired, and the cables may be adjusted as to length of train by setting the brake on the end car and strain- 40 ing or stretching the train to its full length and then adjusting the cables accordingly before the train is started on its journey.

In the operation when it is desired to dump a train-load the brake is again set and the 45 train stretched and the pins 30 are to be removed at the side opposite the direction in which the platforms are to be tilted, provided such pins are in their places. Then by operating the drum 33 in the proper direction the 50 cable at the dumping side will be drawn taut, while the cable at the other side is paid off the drum. The cable at the dumping side will rock the shaft 20, causing the arms 24 to swing the latch 15 or 16, as the case may be, to release it from the projection 14, permitting the 55 chains 10 to be operated by means of the wheels 7 to tilt the platform. After dumping it is obvious that a reverse motion of the drum will shift the several platforms to normal 60 position and also shift the arms 26 into latching position.

Having thus described my invention, I claim as new and desire to secure by Letters Patent—

1. A plurality of connected dumping-cars,

means for holding the car-platforms in horizontal position, and mechanism for simultaneously releasing the holding devices and dumping all of the cars. 65

2. A plurality of connected cars, each car having a side-tilting platform, a rock-shaft 70 supported in each car, dump - controlling wheels mounted on said shaft, the said wheels being notched in the periphery, chains extended over said wheels and having blocks for engaging in the notches, pulleys on the 75 truck of the car around which the chains pass, the ends of said chains being connected to the platform near the sides, means for locking the wheels in normal position, means for releasing the locking devices, and cables extended 80 along the several cars of a train and adapted for operation to dump the several cars simultaneously. 85

3. A dumping-car comprising a truck, a platform having swinging relation thereto, a 85 rock - shaft arranged below the platform, wheels secured to said shaft, the said wheels each being provided with a notch in its periphery, a projection on each wheel opposite the notch, latches mounted to swing on the 90 truck for engaging with opposite sides of said projections, spring connections between the latches of a pair, a shaft arranged below the first-named shaft, downwardly-extended arms on said shaft, rollers carried on said arms and 95 engaging between the latches, chains for engaging with opposite sides of the platform and passing over the wheels, carried by the first-named shaft, blocks on said chains for engaging with the notches of said wheels, rollers on the truck around which said chains pass, an arm extended downward from the lower shaft, pulleys on opposite sides of said arm, pulleys supported by the truck, pulleys 100 attached to the platform, and cables engaging 105 with the several pulleys at opposite sides. 110

4. A dumping - car comprising a truck, a platform mounted to swing laterally thereon, a rock-shaft arranged below the platform and having a crank portion, dump - controlling 110 wheels mounted on said shaft, antifriction-rollers carried by said wheels, the said wheels being notched in the periphery, projections on the wheels opposite the notches, swinging latches for engaging with said projections, a 115 latch - controlling shaft arranged below the first-named shaft, arms extended downward from said latch-controlling shaft, rollers carried by said arms and engaging between the latches, a spring connection between said latch- 120 controlling shaft and the crank of the first-named shaft, and cables for moving said latch-controlling shaft and swinging the platform. 125

5. A plurality of connected dumping-cars, a winding-drum at one end of the train, cables 125 extended along the opposite sides of the cars and reversely wound on said drum, means for holding the platforms of the cars in horizontal

position, and means actuated by said cables for releasing said holding devices and dumping the cars.

6. A plurality of connected dumping-cars, 5 a tender, an engine on said tender, a drum operated by the engine, cables extended from said drum and having connection with the several car-platforms at the opposite sides, pulleys on the car-trucks around which the cables pass, 10 and swinging platforms arranged between the cars.

7. A plurality of dumping-cars, a tender, an engine on said tender, a drum on the tender operated by the engine, cables extended from 15 the drum and connecting with the car-platforms at opposite sides, spring connections between the cables and the terminal car, pulleys on the car-trucks around which the cables pass, and means for locking the platforms of 20 the cars in horizontal position.

8. A dumping - car comprising a truck, a

platform mounted to swing thereon, a rock-shaft arranged below the platform, wheels mounted on said shaft and having peripheral channels, antifriction-rollers arranged in said channels, the side walls of the channels being notched, chains connected at their ends to the platform at opposite sides and passing over the wheels and in the channels, blocks on said chains for engaging in the notches, rollers on the truck around which the chains pass, means for locking the wheels in normal position, and cables extended along the car at opposite sides and operating to dump the platform and to release the locking means. 25 30 35

In testimony whereof I have signed my name to this specification in the presence of two subscribing witnesses.
